213,506

COMBINED PLAYHOUSE AND SLIDE

Helen J. Rosing, 235 77th Ave. N.,
Brooklyn Park, Minn. 55430

Filed Mar. 1, 1968, Ser. No. 10,810

Term of patent 7 years

U.S. Cl. D34—5
Int. Cl. D21—03

FIG. 1 is a front view of the ornamental design for a combined playhouse and slide.

FIG. 2 is a rear view of the design shown in FIG. 1;

FIG. 3 is a top view of the design shown in FIG. 1; and

FIG. 4 is a side view, taken from the right side, of the design shown in FIG. 1.

FIG. 5 is a left side elevational view of FIG. 1.

I claim:

The ornamental design for a combined playhouse and slide, as shown.
